C. L. FITCHET

COMBINED GLOBE HOLDER AND REFLECTOR

Filed March 27, 1922

FIG 2

FIG 3

Inventor

Charles Lee Fitchet

By N. E. Dunlap
Attorney

UNITED STATES PATENT OFFICE.

CHARLES LEE FITCHET, OF LANCASTER, PENNSYLVANIA.

COMBINED GLOBE HOLDER AND REFLECTOR.

Application filed March 27, 1922. Serial No. 547,053.

To all whom it may concern:

Be it known that I, CHARLES LEE FITCHET, a citizen of the United States of America, and resident of Lancaster, county 5 of Lancaster, and State of Pennsylvania, have invented certain new and useful Improvements in Combined Globe Holders and Reflectors, of which the following is a specification.

10 This invention relates broadly to supports for lamp globes and shades, and more specifically to a hanger or holder for such globes or shades.

15 The primary object of the invention is to provide an improved form of globe or shade holder of the general type which embraces and is supported by the electric lamp receiving socket.

20 A further object is to provide a globe holder in which the globe is adequately supported without the employment of attaching screws, spring fingers or clips, or other means requiring adjustment.

25 A still further object is to provide a device of the character mentioned which, while it is mounted in embracing relation to a lamp socket, may be supported in such manner that its weight is not wholly imposed upon the socket, thus eliminating the chance 30 of the inner and outer shells, of the socket becoming detached, one from the other, due to weight imposed thereon.

35 Other important objects of the invention will hereinafter be made apparent in the description in which reference is had to the accompanying drawings, in which—

Figure 1 is a top plan view of the invention;

40 Figure 2 is a section elevation of the same illustrating its application; and—

Figure 3 is a fragmentary section on line 3—3, Fig. 2.

45 Referring to said drawings, 1 indicates each of two identical complementally arranged sections which together constitute a support or holder for a glass globe, as 3. Said holder, which is approximately of bell-shape, has an internal annular rib 4 located adjacent to the lower edge thereof, said rib 50 being adapted to receive closely within its embrace the reduced neck portion of the globe 3 whereby the latter is supported.

55 The holder has an upright neck 5 for more or less closely embracing a suspended lamp socket, and formed on the opposite

sides of the neck portions of each of the holder-sections 1 is an ear 6. The ears of the two sections are disposed in abutting relation and have projected therethrough short bolts 7 whereby said sections are rigidly secured together.

60 Said neck 5 is preferably provided inferiorly with a plurality of vertical grooves or flutes 8 which constitutes passages for air, means being thus afforded for maintaining the embraced socket relatively cool. Ventilation openings of any suitable form, as the openings 9 and 10, may be provided in the holder sections, the same serving as outlets for heated air and providing for 65 the creation of a rapid circulation of air whereby the interior of the globe and the lamp are maintained in relatively cool condition.

70 The meeting edges of the holder sections are shaped to form a close joint for preventing the passage of light, a flange 11 being formed on the edge of one section for overlapping the plain edge of the other section, as is best shown in Fig. 3.

75 Provided upon the upper end of each of the neck portions of the holder sections is an apertured lug 16 to which may be attached the lower end of an insulated wire or cord which has its upper end tied to the 80 socket suspension cord or other support, whereby the lamp socket is relieved of the weight of the holder and attached parts.

85 A reflector 12 of suitable shape is disposed in encircling relation to the neck 5 of the holder, the same having oppositely disposed inwardly extending integral lugs 13 adapted to be received between the ears 6 of the holder sections in complementary recesses 14 provided therefor in the confronting faces of said ears and to be secured in place by the bolts 7 by which said sections are attached one to the other, said lugs having bolt holes 15 therein for the reception 90 of said bolts.

100 Said reflector is mounted with its upper edge encircling the holder above the positions occupied by the ventilating openings 9 and 10 and also with said edge spaced away from said holder. Thus, air heated in passing through the globe and about the lamp discharges through the openings 9 and 10 beneath the top of the reflector, and this heated air is driven outward through the restricted space intermediate the holder 105 110

and the upper edge of the reflector by the cold air which rises beneath the reflector, producing a suction which induces a draft for increasing the volume of air passing through the globe, whereby the lamp is maintained in a relatively cool condition.

While the holder and reflector may be made of any suitable material or materials, it is at present contemplated to employ 10 aluminum having the inner or under light-reflecting surfaces provided with a mirror-like polish.

As is apparent from the foregoing description, the invention provides a simple 15 and efficient combined holder and reflector for electric lamp shades and globes, the construction being such that the shade or globe is firmly supported without the use of the set screws ordinarily employed for attaching such globes, and that, consequently, 20 breakage resulting from the use of such screw is obviated.

What is claimed is—

1. A combined globe support and reflector 25 for electric lamps, comprising a two-part holder of substantially bell shape having a neck for embracing a suspended lamp socket, the two parts of said holder being identical in form and complementary one to the other, 30 corresponding ears formed on the neck portions of said two parts, attaching bolts directed through said ears, said holder having an internal annular rib adjacent to its lower edge for embracing the neck of a globe, and 35 a reflector encircling said holder and having supporting lugs mounted upon said bolts.
2. A combined globe support and reflector 40 for electric lamps, comprising a two-part holder of substantially bell shape having a

neck for embracing a suspended lamp socket, the two parts of said holder being identical in form and complementary one to the other, corresponding ears formed on the neck portions of said two parts, attaching bolts directed through said ears, said holder having an internal annular rib adjacent to its lower edge for embracing the neck of a globe, and 45 a reflector encircling said holder and having supporting lugs mounted upon said bolts, 50 and an apertured lug carried by the neck portions of each of the two parts of the holder for the reception of a suspension cord.

3. A globe support for electric lamp sockets, 55 comprising a two-part holder of approximately bell shape having a neck for embracing a lamp socket, said holder having an internal annular rib for embracing the neck of a globe and being provided with side-opening ventilation openings in the body 60 thereof, attaching ears carried by each of the two parts of the holder, securing means directed through said ears, and a reflector encircling said holder with its upper edge 65 located above the level of said openings, said upper edge being also spaced from said holder to provide an intermediate air passage, said reflector having formed thereon supporting lugs which are received between the ears of said two parts of the holder and 70 which are mounted on the securing means for the latter.

In testimony whereof, I affix my signature in presence of two subscribing witnesses.

CHAS. LEE FITCHET.
